UNITED STATES PATENT OFFICE.

CHARLES F. WELSH, OF DETROIT, MICHIGAN.

TUBE-WINDING MACHINE.

1,002,888.

Specification of Letters Patent. Patented Sept. 12, 1911.

Application filed September 23, 1910. Serial No. 588,340.

To all whom it may concern:

Be it known that I, CHARLES F. WELSH, citizen of the United States, residing at Detroit, county of Wayne, State of Michigan, have invented a certain new and useful Improvement in Tube-Winding Machines, and declare the following to be a full, clear, and exact description of the same, such as will enable others skilled in the art to which it pertains to make and use the same, reference being had to the accompanying drawings, which form a part of this specification.

This invention relates to tube winding machines.

It has for its object an improved machine adapted to wind and shape a prismatic form of tube, using long ribbons of paper that are wound onto the mandrel to produce what is known as spirally wound tubes. In the production of such a spirally wound tube the mandrel turns on its own axis and the tube is formed between the point and the heel of the mandrel, the paper forming the tube being constantly added to the tube or wound at that end thereof which lies toward the heel of the mandrel, and the formed or shaped part of the tube is pushed off from the end of the mandrel and is severed in lengths as may be desired.

In the drawings:—Figure 1, is a plan view of part of the tube winding mechanism. The journal bearing is shown in section. Fig. 2, is a detail of that part of the mandrel and its attachments in which the special features of this invention are found. Fig. 3, is a cross section on the line 3—3 of Fig. 2. Fig. 4, is a plan view of the heel end of the mandrel.

The frame 1 of the machine supports the head or bearing 2 in which is the cylindrical journal end 3 of the mandrel 4. The mandrel 4 consists primarily of a track member or race member, which, in the form shown, is cruciform in shape and is adapted to produce a substantially square tube; but the prismatic form of tube may have any number of sides and the mandrel used will comprise a grooved body or member having as many projecting ribs as there are angles to the prismatic tube to be formed. In every case, however, the construction will be mechanically the same as that shown in the form here illustrated in which the mandrel is adapted to produce a square tube, and consists of four ribs 6, 7, 8 and 9. In the form shown two of the ribs 8 and 9 are

grooved, the two driving chains being sufficient to move the tube along a mandrel which is adapted to produce a rectangular tube. The body part 19 of the mandrel is either integral with or secured firmly to the journal 3 and for purposes of clearness this grooved part of the mandrel will be hereinafter called the prismatic portion of the mandrel as distinguished from the journal 3. The term "prismatic" is not strictly correct, because the side surfaces are preferably formed with reentering curves 10, against which the paper or board of which the tube is made does not engage; the depth of the curve is quite immaterial. In each of the grooves 11 and 12 is located a chain similar to a sprocket chain with links shaped to present a bearing surface at the corners of the prismatic member 9, and to engage so closely the one with another as to produce a continuous line along the edge 13. On the run between the ends of the prismatic part of the mandrel at the delivery or point end of the mandrel each chain passes over a rag wheel or sprocket wheel 14 and at the heel end of the mandrel the sprocket chain passes over a similar rag wheel or sprocket wheel 15.

The shaft of the sprocket wheel 15 extends to the side of the mandrel, and on the terminal of the shaft is mounted a gear 16 that meshes with a fixed toothed wheel 17 mounted on the bearing 2. Inasmuch as the work required of the intermeshing wheels 16 and 17 is light, it being only required that the work done thereby move the chain and the tube wound upon it, while the tube will nearly and sometimes quite move itself, the wheels 16 and 17 may be arranged as skew wheels, that is, the strain on the wheel 16 may be not directly perpendicular to the axis thereof but askew thereto. The teeth of the wheel 16 in this case are preferably cut somewhat in the shape of a spiral gear so that the contacting teeth lie in a radial plane with the larger wheel 17.

The rotation of the mandrel on its own axis is produced by the belt 12 which drives the mandrel and which is itself propelled by the pulley 6. The rotation of the mandrel which carries the wheel 16 in revolution with it causes a corresponding rotation of the wheel 16 and drives the chain and carries forward the tube. The form of driving chain which has been described is adapted to a mandrel having an outline for tube forming purposes which is equivalent to a

prism; and in which there is arranged in grooves at corners of the prism, or in some of the grooves at corners of the prism members which move to carry the tube longitudinally of the mandrel.

Other forms may be easily and readily substituted for the chain which is herein described which would produce substantially the same results and would come within the spirit of this invention, which comprises a prismatic mandrel or a mandrel adapted for the winding of a prismatic shaped tube, in which provision is made for automatically shifting the making tube along the mandrel by means of members provided with bearing points for the tube which travel lengthwise of the mandrel while the mandrel is revolving.

What I claim is:—

1. In a tube winding machine, in combination with a frame, a fixed head thereon, a gear connected with said head, a mandrel rotatably held by said head, tube bearing members located in said mandrel and continuously movable with respect thereto, and means engaging between said tube bearing members and the gear on said head whereby the tube bearing members are actuated, substantially as described.

2. In a tube-forming machine, in combination with a rotatable mandrel, a tube bearing member upon said mandrel having a bearing surface adapted to move continuously from the heel to the point of said mandrel, an inter-acting device between said tube bearing member and a fixed part of the machine adapted to produce the actuation of said tube bearing member contemporaneously with the rotation of said mandrel, substantially as described.

3. A tube forming machine, having in combination a rotatable mandrel, a belt member adapted to travel lengthwise on said mandrel and return and to expose as a bearing surface only that part traveling from the heel of the mandrel to the point, means for propelling said belt member and

gears carried by said mandrel and rotated by contact with stationary portions of said machine adapted to actuate said propulsive means, substantially as described.

4. In a tube winding machine, in combination with a frame, a rotatable mandrel, endless tube propelling and bearing members sustained by said mandrel and arranged to afford the bearing points of said bearing members continuous motion lengthwise the mandrel in one direction simultaneously with the rotation thereof, and means for driving said tube propelling members by contact with stationary parts of the frame, substantially as described.

5. In a tube winding machine, in combination with a rotatable mandrel, endless tube bearing members carried thereby and having bearing points continuously moving lengthwise said mandrel in one direction and means whereby the rotation of said mandrel actuates said tube bearing members, substantially as described.

6. In a tube forming machine, in combination with a mandrel rotatably mounted in said machine, a tube bearing member on said mandrel having bearing points moving continuously lengthwise said mandrel, an interacting device between said tube bearing member, and a fixed part of the machine, adapted to produce the actuation of said tube bearing member contemporaneously with the rotation of said mandrel.

7. In a tube forming machine, in combination with a mandrel rotatably mounted in said machine, rotating tube bearing members, a pair of toothed wheels adapted to travel along a fixed portion of said machine thereby actuating said bearing members, substantially as described.

In testimony whereof, I sign this specification in the presence of two witnesses.

CHARLES F. WELSH.
